UNITED STATES PATENT OFFICE.

JOHN H. EICKERSHOFF, OF CINCINNATI, OHIO, ASSIGNOR, BY MESNE ASSIGNMENTS, TO MATTHEW GOTTFRIED, OF CHICAGO, ILLINOIS.

MASH-TUB MECHANISM.

SPECIFICATION forming part of Letters Patent No. 413,041, dated October 15, 1889.

Application filed November 21, 1887. Serial No. 255,725. (No model.)

To all whom it may concern:

Be it known that I, JOHN H. EICKERSHOFF, a citizen of the United States, residing at Cincinnati, Hamilton county, Ohio, have invented 5 new and useful Improvements in Mash-Tub Mechanism, of which the following is a specification.

My invention relates to mechanism used in connection with the mash-tub in distilleries, breweries, &c.; and it consists, first, of stirring and discharging mechanism adapted to be elevated and depressed at will relatively to the mass of grain to be treated, and capable of operating at any elevation or at a 15 constantly-changing elevation within its fixed limits, and, secondly, in the details of construction and arrangement by which these results are accomplished.

Mechanism embodying my invention is exhibited in the accompanying drawings, in which—

Figure 1 is a general sectional elevation of the mash-tub containing the mashing and discharging mechanism, parts of the mechanism 25 being also sectioned to show the construction; and Fig. 2, a detail plan of part of the mechanism, showing the arrangement of the adjustable blades employed in mashing and discharging.

Referring now to the drawings, A designates an ordinary mash-tub cylindrical in form, provided with perforated screen a, constituting a false bottom for drainage purposes; B, a perforated pedestal or block centrally located upon and secured to the bottom, and C the discharge-conduit opening through the bottom at one side near the outer wall of the tub, and ordinarily closed by a disk-valve c, which, upon occasion, is lifted from its seat 35 by a hook-rod from above. The tub is ordinarily located upon the floor-supports of the building, as indicated by the sectioned I-beams of the drawings, which do not require a special reference-letter.

Carried upon the pedestal-block B is a vertically-perforated spindle D, which, with its radial arms d d', is preferably formed of cast-iron, its axial perforation being squared to receive the squared upper portion of a central vertical driving-shaft S, which is carried 45 through a fixed journal-block y at its upper

end, and is stepped into a fixed journal and supporting-block y' at its lower end, the lower part of said shaft being cylindrical to a point just above the pedestal-block B, through 55 which it passes. The shaft S is thus extended from a bearing at a convenient distance above the mash-tub A to a support at a convenient distance below the bottom of the tub, and is driven by a suitable gearing x x' from 60 a counter-shaft x² at or near its lower extremity. A suitable stuffing-box y² is arranged to embrace the shaft S at the point of vertical emergence from the pedestal-block B and prevent leakage through the orifice at that 65 point.

Immediately upon the pedestal-block B, and intervening between it and the bottom of the spindle D, is a bevel-gear b, suitably recessed at its upper side to form a seat for the spindle D, which is held in place by an annular collar b', covering a projecting flange of the spindle. This connection also causes the gear b to be elevated by the spindle when the latter is elevated, for reasons to be presently explained. The gear b is provided with one or more depending guide-rods r, which are rigidly secured to the gear b and pass vertically downward through suitable perforations in the pedestal-block, having also suitable stuffing-boxes z to prevent leakage. The rods r serve as pins or stops to prevent rotation of the gear b at any elevation, yet permit free elevation and depression.

The rotating stirrers, as indicated at f' f² 85 f³ f⁴, are crank-arms carried upon and by a horizontal shaft f, journaled at one end in a suitable lateral socket upon the spindle D and supported near its outer end by a bracket-arm d³, depending from the main arm d' of the 90 spindle. The stirrers are of the usual or any desired construction and need not be further described. They are operated by the rotation of their carrying-shaft f by means of a bevel-pinion f⁵, secured thereto and meshing 95 with the relatively-fixed bevel-gear b. As the spindle D rotates in its horizontal plane, carrying the arm d' and the shaft f with it, the pinion f⁵ is carried upon the relatively-fixed gear b, causing the rotation in a vertical plane 100 of the shaft f and the stirrers.

The general rotation of the spindle D is ef-

fected by means of the squared portion of the shaft S engaging in the squared aperture of the spindle, and by the prolongation of the squared shaft S upward such rotation continues at any elevation of the spindle and its connected parts. The opposite arm d of the spindle carries journaled through the same a number of vertical shafts e, in series successively outward from the spindle D. These shafts pass through a fixed holding-brace g, parallel with and below the arm d, extending from the spindle through a bracket-arm d², similar in form and relative arrangement to the bracket-arm d³, supporting the shaft f, as already described, and are terminated below by flat blades e', which, in the general action of the spindle, sweep in circular concentric paths horizontally. The terminals of the shafts e, projecting above the arm d, are provided with corresponding cranks e², all connected by a connecting-rod to a common set-lever e³, by which the relative inclination of the blades to their circular paths may be adjusted and secured at any desired inclination by a rack-bar e⁴. In practice, however, I prefer to leave the outer blade e' unconnected with the adjusting mechanism and fixed in position, owing to the location of the discharge-orifice somewhat within the circular boundary of the tub, so that it may always act centripetally upon the mass of grain, while the others act centrifugally.

It remains now to describe the elevating mechanism. The upper end of the spindle D is grooved circumferentially to carry an annular supporting-yoke h. In my practice I diminish friction at the upper surface of the yoke by an annular groove with steel friction-balls, as indicated; but as this is a mechanical detail having no direct bearing upon the invention, I do not designate them by letters or make further reference to them. By means of suitable projecting ears the yoke h is connected through hangers j j with a similar yoke i, threaded upon a screw-shaft s, arranged in the extended axis of the shaft S, but wholly independent of it. The screw-shaft s is journaled above in a suitable supporting-bracket v and below in the bearing y of the shaft S, and carries a bevel-gear k, receiving power through a pinion l from a counter-shaft m. I have shown in the present case two chain or belt wheels o and n, of different diameters, indicating different speeds at which the shaft m may be driven in its opposite revolutions. Both these wheels run idly upon the shaft m, which is connected with one or the other driving-wheels by a shifting clutch p, carried upon the shaft by a "pin-and-feather" connection, and shifted into one or the other engagement by a pivoted bell-crank arm q. The bell-crank is operated automatically to stop the rotation of the screw s when the proper elevation or depression of the apparatus is attained by the following mechanism: To the screw-yoke i is attached a vertical rod or standard t, carried

up and down with it and passing through or adjacent to the horizontal arm q' of the bell-crank shifter q. Stops t' and t² upon this rod engage the arm q' in either direction and withdraw the clutch p from engagement with the wheel o or n, as the case may be. This, however, is a mere safety device to prevent the machine overrunning beyond its proper limit in either direction.

The operation is as follows: When the parts are in the positions indicated in the drawings and the central shaft S rotated by its gear-connections below, the spindle D is rotated with it and the arms d d' sweep around, carrying their depending mechanism. The rotating stirrers f f², &c., perform their usual and proper functions, and the blades e' may be set to coincide lineally as nearly as desired with their paths of movement. At the conclusion of the "mashing" operation the rotation of shaft S is stopped and power is applied by the shaft m and gears l k to the screw s, which, acting through the yokes i h and suspending-rods j, lifts the spindle D, its arms d d', and their connected parts, including the bevel-gear b, (which at any elevation is held against rotation by its rod or rods r,) upward wholly clear of the tub contents. After draining off the liquid contents the valve c (which opens through the false bottom a) is removed, and the body of moist grain immediately over it passes downward, leaving an approximately funnel-shaped opening through the body of grain, which otherwise remains as a semi-coherent mass somewhat compacted. The shaft S is now again started in operation, the spindle D and arms d' swinging around, as before, but above and clear of the grain contents of the tub. At the same time power is applied to the screw s, which thus slowly carries the spindle and connected mechanism downward by gradual movement. The blades e', being set at an angle across their concentric paths, soon begin to act at the surface of the grain, carrying it gradually outward from the center to the circumference until it finds egress at the opening described. Thus layer by layer the grain is discharged into the opening as the mechanism descends until all is discharged, and the blades having reached their lowest limit further descent is automatically arrested by the stops t', as described, when the tub may be refilled for another operation.

It will be observed that as the spindle rises and falls the bevel-gear b rises and falls with it without rotation, and always preserves its proper relation to the pinion f⁵.

I claim and desire to secure by Letters Patent of the United States the following:

1. In a mash-tub, the combination of a central vertical driving-shaft, a horizontal arm centrally pivoted thereon and carried thereby, but free to be moved vertically on the driving-shaft, stirrers or beaters carried upon said horizontal arm and operated by the ro-

tation of the driving-shaft, and means for automatically raising or lowering said horizontal arm while in rotation and automatically stopping said raising and lowering at predetermined limits, substantially as described.

2. In a mash-tub, the combination, with a central spindle D, having stirrers and scrapers suitably supported thereon, and means for raising and lowering said spindle, of the bevel-gear b, loosely supported by said spindle and meshing with the gearing f⁵, for rotating shaft f, said bevel-gear and gearing so adapted as to be raised and lowered with the spindle D and remain in mesh, substantially as described.

3. In a mash-tub, the combination, with a central spindle D, having stirrers and scrap-

ers suitably supported thereon and carrying the yoke h, and a shaft S, adapted to rotate said spindle, of a screw-shaft s, mounted upon shaft S, but rotatable independently thereof, and the screw-yoke i, engaging with said screw-shaft s, and connections between said screw-yoke i and yoke h, for raising and lowering the spindle D, substantially as described.

In testimony whereof I have hereunto set my hand in the presence of two subscribing witnesses.

JOHN H. EICKERSHOFF.
